TOY CHEST

John Schoendorf, 180 Bedford Ave., Merrick, N.Y.

Filed Mar. 15, 1961, Ser. No. 64,314

Term of patent 7 years

(Cl. D34—15)

FIG. 1 is a perspective view taken from one side of the toy chest in the closed position,

FIG. 2 is a reduced perspective view taken from the other side of the toy chest in the open position,

FIG. 3 is a reduced side view of the toy chest,

FIG. 4 is a reduced front view of the toy chest, and

FIG. 5 is a reduced rear view of the toy chest.

The dominant features of my design reside in the portions shown in full lines.

I claim:

The ornamental design for a toy chest, as shown and described.
